Penie Davis Merant, Esq.,
His Attorneys,

UNITED STATES PATENT OFFICE

HOWARD JOHN FOUNTAIN, OF LONDON, ENGLAND, ASSIGNOR TO THE CLARKSON & THIMBLE TUBE BOILER COMPANY LIMITED, OF LONDON, ENGLAND

STEAM GENERATOR OR WATER HEATER

Application filed May 20, 1932, Serial No. 612,471, and in Great Britain May 26, 1931.

This invention relates to steam generators or water heaters of the kind comprising an annular water chamber with closed ended water tubes or thimbles or with loops extending inwards into a heating space, through which the combustion gases from a burner are passed, the heating space being bounded on its inner side by a baffle member.

In accordance with the present invention the baffle member which is hollow is fitted with an inlet pipe and an outlet pipe for the supply and withdrawal from the baffle of air or water so that the baffle may be used as an air heater for heating the air to be supplied to the burner, which air is thus supplied in heated condition, or as a water heater separate from the steam generator or water heater proper.

The inlet and outlet pipes may be disposed concentrically one within the other and one of these pipes used to provide a central support for the baffle. A by-pass may be provided between the inlet pipe and the outlet pipe in order to ensure that should the baffle become perforated, the air or water will be short circuited.

An embodiment of the invention is illustrated in the accompanying drawings in which Fig. 1 is a cross section through a steam generator or water heater of the kind referred to having the baffle member arranged as a water heater separate from the steam generator or water heater proper or as an air heater in accordance with the invention. Fig. 2 is a section on the line X—X of Fig. 1. Fig. 3 is a cross section through a steam generator similar to Fig. 1 in which, however, the inlet and outlet pipes are disposed concentrically and a by-pass is provided between the inlet pipe and the outlet pipe.

In the drawings 1 indicates a steam generator or water heater of the kind comprising an annular water chamber 2 with closed ended water tubes or thimbles 3 radiating inwards into a heating space 4, through which the combustion gases from a burner or furnace or engine (not shown) but disposed at the lower end of the generator are passed, the

heating space 4 being bounded on its inner side by a hollow baffle member 5.

In the embodiments shown the baffle member is provided with radiating ribs 6 and a conical bottom which is preferably reinforced and of hematite iron. The interior of the baffle member 5 is connected with a cold air or water inlet supply pipe 7 extending to near the bottom of the baffle and has an outlet pipe 8 for the heated air or water extending from the upper end of the baffle, the pipe 8 leading to the point of consumption or to the burner according as the baffle is used as a water heater or an air heater.

The baffle member 5 is shown in Fig. 1 as suspended in the heating chamber by means of a rod 9 in the usual way but may be suspended solely from the air or water inlet and/or outlet pipes 7, 8. The inlet and outlet pipes 7, 8 may as shown in Fig. 3 be disposed concentrically one within the other and one only of these pipes used to provide a central support for the baffle.

A by-pass 10, shown in Fig. 3, is preferably provided between the inlet pipe 7 and the outlet pipe 8 in order to ensure that should the baffle 5 become perforated, the air or water will not pass direct through the baffle into the heating space.

The baffle member may consist of two cylinders one within the other, the cold air or water being supplied to the inner cylinder and passing out the lower end of the latter into the outer cylinder from which it may be taken to the point of consumption or to the burner.

The baffle may be of cylindrical form as shown or of conical or other form.

I claim:

1. A steam generator or water heater comprising an annular water chamber presenting a flue for combustion gases, water tubes extending into said flue, a hollow baffle disposed within said flue said baffle being closed at its end and being provided adjacent said end with radiating ribs and means whereby said baffle may be used as a heater, said means including an inlet pipe connection extending among said radiating ribs for delivering to said hollow baffle the medium to

be heated and an outlet pipe connection for removing the heated medium therefrom.

2. A steam generator or water heater comprising an annular water chamber presenting a flue for combustion gases, water tubes extending into said flue, a hollow baffle disposed within said flue said baffle being closed at its end and being provided adjacent said end with radiating ribs and means whereby said baffle may be used as a heater, said means including an inlet pipe connection extending among said radiating ribs for delivering to said hollow baffle the medium to be heated and an outlet pipe connection for removing the heated medium therefrom, said connections serving for supporting the baffle member within said flue.

3. A steam generator or water heater comprising an annular water chamber presenting a flue for combustion gases, water tubes extending into said flue, a hollow baffle disposed within said flue said baffle being closed at its end and being provided adjacent said end with radiating ribs and means whereby said baffle may be used as a heater, said means consisting of an inlet pipe connection extending among said radiating ribs for delivering to said hollow baffle the medium to be heated and an outlet pipe connection for removing the heated medium therefrom, said inlet and outlet pipe connections being disposed one within the other.

4. A steam generator or water heater comprising an annular water chamber presenting a flue for combustion gases, water tubes extending into said flue, a hollow baffle disposed within said flue said baffle being closed at its end and being provided adjacent said end with radiating ribs, means whereby said baffle may be used as a heater, said means consisting of an inlet pipe connection extending among said radiating ribs for delivering to said hollow baffle the medium to be heated and an outlet pipe connection for removing the heated medium therefrom, and a by-pass between the inlet and the outlet connections.

In testimony whereof I have signed my name to this specification.

HOWARD JOHN FOUNTAIN.
